UNITED STATES PATENT OFFICE

2,532,267

METHOD OF AND APPARATUS FOR
COMPRESSING VAPORSCurtis D. Chase, Brighton, Mass., assignor to
Boston Marine Works, Inc., East Boston, Mass.,
a corporation of Massachusetts

Application February 9, 1948, Serial No. 7,275

7 Claims. (Cl. 62—115)

1

This invention relates to a method and apparatus for compressing vapors or gases and is characterized in that the fluid which is to be vaporized is used as the compression medium for compressing the vapor or gas.

One object of my invention is to provide a simple means of compressing the vapors or gases without the necessity of maintaining tight working joints between metallic surfaces.

Another object is a simple mechanism for compressing the vapors or gases within the vapor section of an evaporator.

A further object is to maintain a cylindrical body of fluid of predetermined size about the compression areas of the vapor section of the evaporator so as to provide the compression medium.

Another object is to automatically control the volume and the size of this body of fluid by introducing fluid at the center of the fluid body and maintaining a predetermined size of the fluid body by automatically discharging any surplus fluid.

Another object is to maintain the inside diameter of said fluid body substantially constant at all times and under all conditions of operation.

Other objects and advantages of my invention will appear as this description proceeds.

In the accompanying drawings wherein I have disclosed a preferred apparatus for the practice of my invention:

Figure 1 is a side elevation, partly in section, of my apparatus.

Figure 2 is an enlarged view of the vapor section of the evaporator, and

Figure 3 is a section on the line 3—3 of Fig. 2.

I have indicated generally at 10 a conventional evaporator comprising upper and lower tube sheets 11 and 12, shell 13, head 14, and tubes 15.

Surmounting evaporator 10 is a vapor section indicated generally at 17 and consisting of shell 18, flange 18', and supporting head 19 bolted to flange 18' as at 20.

Bolted as at 21 to head 19 is a compression unit consisting of a cylindrical shell 22 and a removable cover 23 assembled thereto as by the cap screws 24.

Shell 22 is preferably a casting provided with an upwardly extending cylindrical portion 25 which is eccentric to the shell 22 and is cored to provide at its bottom spaced openings 26 and 27 and near its top is provided with a pair of ports 26' and 27'.

Rotatable axially about member 25 is a hub 58

2

28 provided with a plurality of spaced radially extending partitions or walls 29 forming chambers 30 which are enclosed at the top and bottom ends of hub 28 by the partitions 31.

5 In the rotation of hub 28 about member 25, each chamber 30 successively communicates with the ports 26' and 27' by means of ports 32 formed in the center of the hub.

Hub 28 extends beyond supporting plate 23 and is sealed by means of a conventional stuffing box consisting of a packing 33, gland 34, and studs 35, and is keyed and bolted as shown to the driving shaft 36 of a motor or other power source M.

15 If desired, I may secure to the bottom of member 22 spaced eccentric but axially parallel cylindrical members 37 and 38 which constitute a vapor trap. Inner member 38 communicates at its upper end with passage 27 and is open at its lower end to outer member 37. Outer member 37 is closed at its bottom and has openings 39 in its side wall communicating with the vapor chamber 40 defined by shell 18 and member 22.

20 Connecting with passage 26 is tube 41 which passes through tube sheet 11 and discharges into evaporator chamber 42.

The operation is as follows:

Assuming that evaporator chamber 42 is filled with fluid which has previously been evaporated to the level indicated at 45, and also fluid under pressure has been admitted through pipe 43 to the chamber 44 which is defined by lower tube sheet 12 and head 14 and with which chamber the tubes 15 communicate at their lower ends.

35 The fluid from chamber 44 passes along tubes 15 into vapor chamber 40 until it reaches a predetermined level indicated at 46 in Fig. 1.

For starting purposes auxiliary heat from any suitable heat source (not shown) is applied to the fluid in chamber 44 and vaporizes this fluid, filling chamber 40 with hot vapors.

40 Part of the fluid below level 45 is withdrawn through pipe 47 by pump 48 and pumped through pipe 49 into the compression chamber 50 which is defined by members 22 and 28, entering said chamber through inlet opening 51 in supporting head 23 and being immediately acted upon by the centrifugal force developed by the rotation of members 28, 29 and 31, forming a cylindrical body or ring of fluid 52 within member 22.

45 When this body or ring of fluid attains a predetermined internal diameter, some of the fluid is expelled by centrifugal force through discharge 53 in head 23 and is returned through pipe 54 to chamber 44.

This operation is continuous and automatic and insures that the body of fluid 52 is maintained at maximum compressing position. This body or ring of fluid 52, being located eccentrically to the rotating members 28, 29, and 31, forms increasing areas 55 thereby sucking the vapors from chamber 48 through inlets 39, 27 and 27' and ports 32 into areas 55. As soon as each area 55 passes the center of eccentricity of member 25 said area 55 decreases in size (see Fig. 3) thus compressing the hot vapor within area 55 between the fluid ring 52 and the hub member 28 and discharges through ports 32, 26', 26 and tube 41 into evaporator chamber 42 above level 45. This hot compressed vapor discharged into chamber 42 gives up its heat of compression by contact with tubes 15 containing the incoming fluid to be compressed thus creating more vapor from said fluid.

The product of this operation may be taken off through pipe 56 and sent to any suitable storage chamber (not shown).

In a typical installation, I found that by using the fluid to be evaporated as the compression medium, heat losses were reduced to the minimum and that the internal compression unit mounted within the evaporator greatly increased the over-all efficiency of the apparatus.

Various modifications in method and apparatus may obviously be resorted to within the spirit and scope of my invention as defined by the appended claims.

I claim:

1. Apparatus for compressing vapors or gases, comprising a compressor having a stationary casing member and an internal rotary member, said rotary member being provided with a plurality of spaced ports around its circumference and said casing member having a portion extending axially into said rotary member and provided with spaced ports for successive registration with the ports of the rotary member to establish suction and compression areas about the circumference of said axial extension, said axial extension also having an inlet and an outlet passage, a vapor section surrounding said compressor and having a vapor chamber with which said inlet passage communicates, an evaporator section associated with said vapor section and having an evaporator chamber with which said outlet passage communicates, means for supplying fluid to said evaporator section for evaporation therein, means for withdrawing a portion of the evaporated fluid from said evaporator section and utilizing it as a compression medium by sending it to the compressor, and means for returning any excess fluid to the evaporator section.

2. The apparatus of claim 1, and means for establishing a cylindrical fluid ring eccentrically of the rotary member of the compressor, and means for controlling the size and internal diameter of the fluid ring.

3. The apparatus of claim 2 in which the means for controlling the size and internal diameter of said fluid ring consists of an inlet and an outlet acted upon by centrifugal force, the inlet being so located as to increase the size and diameter of the fluid ring and the outlet being so located as to decrease the size and diameter of the fluid ring.

4. The method of compressing vapors or gases, consisting in the following steps: supplying fluid to be vaporized to an evaporator vessel, using a portion of the evaporated fluid as a compression

medium by withdrawing the same from the evaporator vessel and sending it to a compressor consisting of a stationary casing member and an internal rotary member, establishing by centrifugal force a cylindrical fluid ring eccentrically of the rotary member, controlling the size and internal diameter of said fluid ring by means of an inlet and an outlet acted upon by centrifugal force, the inlet increasing the size and diameter of the fluid ring and the outlet decreasing the same whereby to maintain substantially constant the internal diameter of said ring, returning any excess fluid to the evaporator vessel, and sending from the compressor substantially all of hot compressed vapors or gases to the evaporator vessel whereby to heat the incoming fluid in said vessel and create more vapor or gas from said fluid.

5. In apparatus having a vapor chamber and an evaporator chamber, a compressor within the vapor chamber and discharging into the evaporator chamber, means for supplying fluid to the vapor chamber, means for utilizing a part of the evaporated fluid as a compression medium by sending it to the compressor, and means for sending the hot compressed vapors or gases from the compressor in heat exchanging relation to the vapor chamber for heating the incoming fluid in said chamber and thereby creating more vapors or gases from said fluid.

6. Apparatus for compressing vapors or gases comprising a vapor chamber adapted to receive liquid to be vaporized; an evaporator chamber in heat exchanging relation with the vapor chamber; a compressor adapted to draw vapor from the vapor chamber, to compress and thereby to heat said vapor, and to discharge said vapor into the evaporator chamber, whereby liquid in the vapor chamber is vaporized under reduced pressure, the compressed hot vapor in the evaporator chamber serves to heat the liquid in the vapor chamber thereby promoting vaporization of the liquid in the vapor chamber, and the vapor in the evaporator chamber condenses leaving a residue of liquid in the evaporator chamber; and means for utilizing a part of the condensed liquid in the evaporator chamber as a compression medium by sending it to the compressor.

7. Apparatus for compressing vapors having in combination a vapor chamber adapted to receive liquid to be vaporized, an evaporator chamber in heat exchanging relation to the vapor chamber, a compressor within the vapor chamber adapted to compress and thereby to heat vapor in the vapor chamber and to discharge the said compressed vapor into the evaporator chamber, whereby the compressed vapor in the evaporator chamber serves to heat the liquid in the vapor chamber thereby promoting vaporization of the same, and the vapor in the evaporator chamber condenses leaving a residue of liquid in the evaporator chamber and means for utilizing liquid in said compressor in part as the compression medium.

CURTIS D. CHASE.
